INSECTICIDE BOMB

Gregory Brown, Bridgeport, Conn.

Application September 15, 1944, Serial No. 554,230

1 Claim. (Cl. 299—150)

1

This invention relates to dispensing apparatus for use in connection with the dispersion of insecticides.

The patent to Goodhue et al. No. 2,321,023 describes a method of producing insecticidal aerosol which involves confining in a receptacle under superatmospheric pressure a liquified gas containing in solution a suitable insecticide and releasing the receptacle contents as desired through a discharge orifice into the atmosphere. The receptacle contents are forced out into the atmosphere by the high vapor pressure of the liquefied gas and the liquid solvent instantly evaporates into the atmosphere separating the solute into particles of colloidal dimensions and leaving them suspended in air in the form of an aerocolloid which is known as aerosol.

An object of this invention is an inexpensive and highly efficient device for releasing and dispersing insecticides in accordance with the Goodhue et al. method.

Other objects, novel features and advantages of this invention will become apparent from the following specification and accompanying drawings, wherein:

Fig. 1 is an elevation partly broken away of an insecticide bomb embodying the invention;

Fig. 2 is an enlarged fragmentary view through the release mechanism;

Fig. 3 is a section on the line 3—3 of Fig. 2, and

Fig. 4 is an enlarged fragmentary section similar to Fig. 2.

In the drawings, 10 is a receptacle of any suitable construction having at one end an aperture into which is fitted a tubular member 11 having a gas-tight fit with the container. The member 11 has a central bore 12 of varying diameter and a pipe 13 has one end projecting into the bore with its remaining end arranged near the opposite end of the receptacle 10. A portion of the bore 12 is shaped to provide a valve seat 14 with which co-operates a valve 15 arranged in an enlarged portion 12a of the bore. The valve 15 is carried by a plug 16 arranged in the bore 12 and having threaded connection with the inner surface thereof at 17. In the plug 16 is a central passageway 18 having its inner end terminating above the tip of the valve 15 and having a cross channel 19 communicating with the chamber formed by the enlarged portion 12a of the bore 12. Rotation of the plug 16 causes axial movement of the valve 15 into and out of engagement with the valve seat 14.

A cap 20 has a central aperture 21 of slightly larger cross-section than the plug 16 and a

2

threaded portion 22 screwed onto the tubular member 11 with the plug extending through the aperture. A thin sleeve 23 of Babbitt metal snugly surrounds the plug 16 and has a flange 24 resting on the outer end of the member 11. The end of the sleeve 23 away from the flange 24 projects through the aperture 21 in the cap 20 and fills the gap between the aperture periphery and the plug surface. A ring 25 of flexible material such as neoprene surrounds the bushing 23 and is contained in an inverted cup 26 arranged in the cap 20 and having an aperture through which the sleeve 23 extends with the rim of the cup adjacent said flange.

15 A fluted rod 27 is arranged in the passageway 18 and has upper and lower ends oblique with respect to the longitudinal axis thereof. A bushing 28 is threaded into a tapped recess 29 in the outer end of the plug 16 and receives the upper end of the rod 27 in a central bore 30 which terminates in a restricted orifice 31. A flanged disk 32 is fixed to the plug 16 and provides means for effecting rotation thereof as well as affords protection to the cap 20.

25 Under normal conditions, the plug 16 is so arranged that the valve 15 engages the seat 14 thereby sealing the receptacle and the receptacle contains under superatmospheric pressure a liquefied gas containing an insecticide in solution. An insecticide of this character is disclosed in U. S. patent to Goodhue, No. 2,306,434. In order to make use of the device, the plug 16 is rotated through the medium of the disk 32 to disengage the valve 15 from the seat 14 whereupon 30 the contents of the container pass through the pipe 13 and around the valve 15 into the cross channel 19 and then through the grooves in the fluted rod 27 to the orifice 31 from which they are discharged into the atmosphere. The oblique 35 face at the end of the rod 27 insures free flow of liquid to the orifice 31 irrespective of the position of the rod in the passageway. Operation of the device is discontinued by rotating the disk 32 again to engage the valve 15 with the valve seat 40 14.

A metal-to-metal seal between the rotating and stationary parts of the device is obtained by means of the babbitt sleeve 23 in conjunction with the neoprene washer 25. The thickness of the 45 Babbitt metal sleeve 23 is of the order of .010 inch. Upon screwing down of the cap 20, the flange 24 is forced by the neoprene washer into a gas-tight seal with the end of the plug 16 and the neoprene washer is caused to bulge inwardly 50 radially in such manner and to such extent as to

distort the sleeve 23 inwardly into gas-tight relation to the plug 16.

The fluted rod 27 provides a readily cleanable filter to prevent small particles from clogging the orifice 31. The flow of the liquid through the fluted rod grooves and around the oblique end of the rod produces turbulence in the liquid as well as reduces the pressure so that the liquid is dispersed through the orifice 31 in the form of a dry spray.

In further explanation of the above; as the liquefied gas rises through the grooves of the fluted rod there is apparently a gradual pressure decrease. Therefore, there is time for conversion to the gas phase in a more complete manner, than when the liquefied gas is directly introduced to the atmosphere through an orifice, so the grooves may be made larger than such an orifice. Consequently, there is less chance for the grooves to become clogged with foreign matter than when an orifice is used. The oblique rod end in the space 30 results in the various gas streams being freed from the confinement of the grooves at different locations therein so that turbulence is effected. Any liquid gas escaping from the grooves is whirled around by this effect while the lighter gas phase can escape through the orifice 31. Since the pressure is low in the space 30 any liquefied gas therein rapidly converts to the gas phase. Therefore, the spray from the orifice 31 is free from droplets of liquid gas or, in other words, is dry. The orifice 31 may be made large since it is used to eject the gas phase and is not required to effect the total pressure drop needed for conversion of the liquefied gas to its gas phase. Consequently, there is little chance for this orifice 31 to become clogged.

I claim:

In a device for controlling the flow path through a member having a central passageway terminating at one end in a recess of enlarged di-

ameter and in the other end in a radial passageway, a bushing threaded to said recess and having its bore terminating in a discharge orifice in the exposed end of said bushing and a fluted rod partly received in said bore and partly in said passageway, said rod terminating at each end in a face oblique to the rod axis, said fluted rod forming with the surfaces of said bore and passageway a plurality of channels each terminating in the oblique faces at the opposite ends of said rod.

GREGORY BROWN.
